CONTAINER HOUSING FLUSHING APPARATUS

Cesare C. Campus, Santa Monica, Calif., assignor to Paul A. Campus, Santa Monica, Calif.

Application July 31, 1934, Serial No. 737,715

34 Claims.

(Cl. 4—70)

This invention relates to a tank or container in one piece with a closet bowl, or attached to it by suitable means for the purpose of housing therein, a flush valve and other accessories, such as an air chamber, or a pressure reducing valve, or a strainer etc. or all, for the purpose of eliminating the various inconveniences resulting at present in the use of flush valves in combination with a closet bowl, and to convey any leakage or exhaust from any or all of the said contrivances housed therein, into the bowl, as hereafter described.

(a) *Danger of back-siphoning.*—There is no flush valve at present on the market that can be considered 100% siphon-proof; in fact, even a very small passage caused by corrosion, or by some matter lodged under the piston valve causing a leak of only about a gallon per minute, if vacuum occurs in the supply pipeline, back-siphoning will occur, no matter what type of vacuum breaker, or any other such contrivance is used in combination with a flush valve. Independently of the practicability of such apparatuses, flush valves are at present not supplied with sufficient volume of air to break the vacuum in the supply pipeline; in fact, the largest air inlet that I know of, is only $\frac{1}{8}$ " diameter; whereas to be efficient, an air inlet must be of the same diameter as the inside diameter of the supply pipeline, and must also be suitably located. A flush valve can be considered 100% siphon-proof only when back-siphoning does not occur when the valve is operated under the following conditions, namely:

When the piston valve is completely open;
When no siphon breaker, no check-valve or any other such contrivance is used, and
Whether or not the valve is in good working order.

This invention answers to all these requisites in full by means and in the manner hereinafter described.

A container, the interior of which is kept in constant communication with the atmosphere by means of an opening thereon, housing a flush valve, without the usual tail piece that connects said flush valve to the bowl and conveys the flush water into it, thus leaving an air space between the top of the bowl and the outlet of the flush valve. Under such conditions it is obvious that it will be physically impossible for a vacuum of any intensity and duration to raise a drop of water from the bowl, thus positively preventing back-siphoning. To prevent the water from spilling, but to convey it all into the bowl, a suit-

able funnel or a like contrivance is provided, as shown in the appended drawings, and herein-after described, which has answered the purpose under the most severe conditions, when this invention was reduced to practice and tested, thus proving that it is possible to obtain a 100% siphon-proof flush valve under the most severe conditions above described.

(b) *Noisy flushing.*—To eliminate this, the water is throttled by the control valve; this method is satisfactory as long as no other water is withdrawn simultaneously when the flush valve is operated, otherwise it will fail to work. However, a pressure reducing valve could be used to eliminate this inconvenience, but there is not always an adequate place where it can be installed. An appropriate place would be in the wall, within easy access for inspection or repairs, but in very few cases the possibility for such a rational arrangement presents itself, but a tank or container, housing a pressure reducing valve will solve the problem in the neatest and most practical manner.

(c) *Failure to flush.*—To obtain a quiet flushing when the pressure in the main is too high, say 90 lbs., the water is suitably throttled by reducing the opening of the control valve, but if said 90 lbs. pressure drops to 20 lbs., and the flush valve is operated, the bowl will not flush; of course not for lack of pressure, but, because the reduced passage in the control valve is not sufficiently large to allow the full volume of water obtainable at the 20 lbs. pressure. In fact a flush valve will flush a bowl even at a water pressure as low as 10 lbs. if the full volume of water at this pressure is available. This inconvenience can be eliminated by a pressure reducing valve housed in a tank, which will always give the full volume of water physically possible, at any pressure to which it has been regulated, unless the pressure in the main drops below that at which the pressure reducer is set.

(d) *Hammering.*—This inconvenience is at present also eliminated by throttling the water with the control valve; however, an air chamber, housed in the tank, will better answer the purpose. A pressure reducing valve can also be used, because hammering never occurs at low water pressure; thus it can be seen that the three inconveniences described in paragraphs b, c, and d, can all be prevented by the same medium, namely by a pressure reducing valve.

This tank or container differs from the ordinary flushing tanks at present in use, as it is operated from the side instead of from the front,

and it does not contain the flushing water, but collects all leakage and the exhaust from the auxiliary valve, and conveys them into the bowl, and in combination with the other members 5 housed therein, prevents back-siphoning, noisy flushing, hammering, and failure to flush, in the manner above described.

The foregoing objects and advantages with my subsequent features that may be developed in 10 the description, may be best appreciated from a description read in conjunction with the drawings in which:

Fig. 1 represents an elevation back-view of the apparatus, partially in section.

15 Fig. 2 represents an elevation back-view partially in section of another form of the invention.

Fig. 3 represents a fragment of the elevation side-view in section on line A—F of Fig. 2.

20 Fig. 4, represents a fragment of an elevation back-view, partially in section of another form of the invention.

Fig. 5 represents a plan view of Fig. 4.

25 Fig. 6 represents a fragment of an elevation side-view in section, on lines a—b—c—d of Fig. 5.

Fig. 7 represents a fragment of an elevation back-view of another form of the invention.

Fig. 8 represents a plan view of Fig. 7.

30 Fig. 9 represents another form of the invention when the flush valve is not housed in the tank.

The construction of my invention shown in Figs. 1, 2, 3, 4, 5, 6, 7, 8, and 9, inclusive, is as follows:

7, in Fig. 1 represents a tank or container in 35 combination with a closet bowl, housing a flushing apparatus; this form eliminates back-siphoning, allows the air constantly under the undersurface of auxiliary valve 29 and the water discharging therefrom and any leakage from the flushing mechanism is collected in the tank and conveyed into the bowl. Orifice A is to allow the water from the flush valve to enter the rim through passage C and into the bowl, through perforations under said rim, and with orifice 40 B to allow the leakage collected by the tank to drop into the bowl through passage B and perforations under the rim. Said tank is also provided with port E to connect flush valve 9 with operating handle 8, which protrudes outside the 45 tank to operate said flush valve, and to allow the air to enter the tank; port F to allow supply pipe 8—2 to be connected to flush valve 9, and to also allow the air to enter said container, jet supply conduit 10 carries at the top end, extension 50 55 11, which in combination therewith forms a bolt-like member to fasten tank 7 to bowl 12 by tightening nut 13, the other end of extension 11 carries flush valve 9 protruding at one side; this arrangement eliminates the spud and tail piece which usually connect the flush valve to the bowl, thus leaving a space between the outlet of the valve and the top of the bowl. It is obvious that this non-continuity of conduit from the valve to the bowl positively eliminates back-siphoning under the action of vacuum of any 60 intensity or duration. Funnel 14, inserted into orifice A is for the purpose of preventing the water from overflowing, and to convey the same into the bowl; this is obtained in combination 65 with the bowl, provided with suitably sized passage therein and proportionally sized perforations under the rim to prevent back-building of the water, and in combination with member 15 extending downwardly to a suitable depth, obtains 70 the inrush of air, thus acting as an injector.

This mechanism practically substitutes the usual tail piece which conveys the water into the bowl. Said member 15 is provided at the upper end with ports 16 for the air supply for the free flowing of water from the outlet of flush valve 9, and at the lower end is provided with screen 18 to reduce the noise of the flowing water; also to keep ring 19 in position and to facilitate the removal thereof. Cover 20 of tank or container, when removed, allows free access to the apparatus, and by unscrewing caps 21 and 22, an inspection of the parts can be made, and new parts substituted, if necessary. Slip-joint supply conduit 23 is connected to member 10 by nut 24 and the lower end to hub 25 of bowl 12 by bolts 26. When auxiliary valve 29 is operated, the exhaust water from dash-pot M discharges into the tank through openings 30, located one at each side of the valve shell; rubber gasket 31 is to prevent leakage and to give flexibility, thus preventing possible breaking of the parts when they are assembled, in case of imperfections. All the foregoing described characteristics of members 10, 11, 14, 15, 18, and 19 are a part of this invention, as they all cooperate with the tank to obtain the wanted result, namely; elimination of back-siphoning, to obtain air constantly under the undersurface of auxiliary valve 29, and to prevent spilling of water from the container to the floor.

The major characteristics of flush valve 9 are not here described, as they form the subject of patent pending application Ser. No. 725,438, filed May 14, 1934.

Fig. 2 represents another form of a tank or 35 container, housing a flushing apparatus. This form has the same prerogatives as the forms illustrated in Fig. 1 and described above, but differs inasmuch as it has an air chamber 27 to prevent knocking, and tank 7 is lower and 40 extension 32 is higher, thus creating two containers R and S. Container R substituting funnel 14, shown in Fig. 1 and container S housing air chamber 27, provided with conduit 28, protruding downwardly to prevent the air therein from 45 escaping, thus preventing hammering; one end connected to supply pipeline 8—2, the other end to flush valve 9 by nipple 37; this valve does not differ practically from the flush valve 9 shown in patent pending application Ser. No. 725,438, filed May 14, 1934. Operating handle 8, extension 11, 50 conduit 10 are for the same purpose, and practically the same as shown in Fig. 1 and described above. Passages C, D and ports E and F are of the same character and for the same purpose as 55 those shown in Fig. 1, but orifice B shown in Fig. 1 is substituted by annular space T formed by the inside wall of container S and the outside diameter of air chamber 27. Ring 19 is kept in position by member 15 provided at the upper end 60 with air inlet 16 to ease the flow of water from the flush valve, and at the lower end is provided with screen 18 to minimize the noise of the flowing water, practically the same device as shown in Fig. 1. Cone 14—2 forms an annular space 65 in combination with member 15 which prevents overflow from container B owing to the onrush of the air therein, and also allows the water collected in the tank, to be conveyed through said annular space into the bowl practically in 70 the same way as the annular space T formed by air chamber 27 in combination with container S. Fig. 3 is a fragment of an elevation side-view, sectioned on line A—F of Fig. 2, showing the side structure of bowl 12, tank 7 and cover 29 75

thereof, and only the mechanism structure of the complete jet supply conduit, consisting of extension 11 which in combination with conduit 10 forms a bolt-like member which connects tank 7 firmly to bowl 12, by means of nut 13, and jet supply conduit 23 connected to member 10 with nut 24, and the lower end which carries nozzle 34, is connected to hub 25, protruding from bowl, by means of bolts 26, as shown in Fig. 2; rubber gasket 31 and packing 35 are to prevent leakage and to give flexibility, thus preventing breaking of the parts in case of imperfections thereof, when they are assembled and fastened together.

This Fig. 3 shows more clearly the disposition of passages C, B, and K through which the scouring and refilling water is conveyed into the bowl.

Fig. 4 represents another form of the invention, showing the tank or container housing a pressure reducing valve and a strainer, besides a flush valve.

This form, in addition to being 100% siphon-proof, as the other forms in Figs. 1 and 2, also eliminates the necessity of throttling the control valve, which is customary in the prevention of knocking, or of noisy flushing, and from which method derives the failure of flushing, more specifically described in paragraphs b, c, and d, also the pressure reducing valve eliminates the knocking of the water without the use of an air chamber, as shown in Fig. 2.

This form shows tank 7 in one piece with bowl 12, a pressure reducing valve 36 of an ordinary type, connected to flush valve 9 by nipple 37 and to strainer 38 by nipple 39; this strainer is provided at the lower end with water supply 8—2 entering tank 7 through opening G, provided with leak-proof slip-joint 40; outlet 64 is connected by nipple 39 to pressure reducing valve 36, as more clearly shown in Fig. 6. Flush valve 9 is of an ordinary piston type, and of course is not the same as the three-cycle type that carries a separate jet contrivance, as shown in Figs. 1, 2, and 3, and above described; nevertheless it has some characteristics of its own, namely:

(a) Auxiliary valve mechanism 41 is separate from the body of flush valve 9, and is carried by strainer 38 and connected to valve 9 by slip-joint tube 42 and nuts 43, and is operated by ordinary handle mechanism 8 connected thereto, through perforation E on the tank 7.

(b) Seat 44 of piston valve 45 is elongated downwardly, thus forming a sleeve, which in cooperation with the lower end of valve shell 9, provided with air ports 46 will act as an air injector, either when the flushing water rushes through thus preventing spilling, or under the action of the vacuum, in case it occurs in the supply pipeline, thus preventing back-siphoning.

(c) Outlet 47 for the flushing water is located at one side of the flush-valve shell, carrying member 48 to convey the water into bowl 12 through spud 49 and opening 50, carried by bowl 12. Said member 48 is provided with flange 51, which is connected to flange 52 carried by spud member 49, held firmly together by bolts 53, thus forming the conduit which substitutes the usual tail piece that conveys the flushing water into the bowl. Bolts 53 are suitably disposed to fasten or unfasten them.

(d) The water from dash-pot M discharges into the tank when auxiliary valve 29 is operated by handle 8; this disposition of auxiliary valve mechanism allows the air to enter the valve when under the action of vacuum directly from the atmosphere, instead of as in ordinary flush valves

to pass through the rim ports of the bowl, from which the motive power of the vacuum can draw pollution back into the water supply.

Fig. 5 is a plan view of Fig. 4, showing a fragment of bowl 12 and tank 7, more clearly showing the disposition of the various mechanism housed therein, namely: flush valve 9 carrying offset 54, auxiliary valve mechanism 41 attached thereto by slip-joint conduit tube 42 and nuts 43 and strainer 38 attached to pressure reducing valve 36 connected to flush valve by nipple 37. Perforations 58 on bowl 12 are the usual means to attach the toilet seat to the bowl. Opening 59 and ribs 60 are to convey any water that has been collected in the tank, into the bowl. This type prevents any water from the bowl, if it overflows, to enter the tank.

Fig. 6 is an elevation view on lines A—B—C—D of Fig. 5, which shows a fragment of bowl 12 in one piece with tank 7, which, instead of conveying the exhaust or leakage from the housed mechanism into the bowl from the inside of the tank, conveys said leakage from the outside of the tank, through port 59 and guided by ribs 60, and being located above the level of the upper end of the bowl, in case this overflows, the water from the bowl will be prevented from entering the tank or container. This view shows clearly the construction of strainer apparatus 38, showing clearly the water supply conduit 8—2 discharging into conduit 61 travelling upwardly and entering strainer 62, from which the water, free of any matter enters chamber 63, which is provided with outlet 64 (shown in dotted line to facilitate the reading of this drawing, but the real position is shown in Figs. 4 and 5), connected to pressure reducing valve 36 by means of nipple 39. Cap 65, when removed allows strainer 62 to be taken out by handle 66, to clean it from any matter caught therein. Annular offset 67 from the shell of the strainer is to hold auxiliary valve 41, provided with conduit 42 and nuts 43, to be connected to flush valve 9, as more clearly shown in Fig. 4.

Fig. 7 is another form of the invention, showing a small fragment of bowl 12 in one piece with tank 7. This form has the characteristic of two separate air inlet contrivances to prevent back-siphoning; one is formed by tail piece 70, provided with air ports 46, carrying at the top extension 71, the top end of which is connected to flush valve 9 and the other is formed by air inlet 68, located above the former one, and on the shell of valve 9, provided with conduit 69, discharging the air under the undersurface of piston valve 45, and the undersurface of auxiliary valve 29 is also exposed and for the same purpose as shown in Figs. 1, 2, and 4, and above described. This will allow the air to enter freely into dash-pot chamber M, thus preventing piston valve 60 from opening under the action of the vacuum, as specifically described in Fig. 4, paragraph d. The exhaust from valve 29 through the open bottom 57 of auxiliary valve mechanism 41 drops into tank 7 and passing through opening 59 located above upper end of bowl and guided by ribs 60 is conveyed into the bowl.

In substance, this form shown in Fig. 7 is for the same purpose as the other forms. In fact, the container housing a flush valve, provided with contrivances to prevent back-siphoning, and the air inlet thereof is also supplied from the inside of the tank, by means of ports or perforations thereon; it also houses an auxiliary valve mechanism; the discharge of leakage therefrom is also

collected by the tank, and conveyed therefrom into the bowl, and finally the flush valve is operated by handle mechanism protruding outside the tank.

5 Fig. 8 is a plan view of Fig. 7 showing tank 1, a small fragment of bowl 12 formed in one piece with tank or container 7. It clearly shows the disposition of the flushing apparatus, water supply conduit 8—2 entering from one side of the 10 tank, and connected to flush valve 9, which carries the auxiliary valve mechanism 41 operated by handle 8, protruding from the tank, and port 59 to allow any water dropping into the tank, to be conveyed by means of ribs 60 into the bowl. 15 Fig. 9 shows container 7 housing a contrivance to prevent back-siphoning, almost similar to the one shown in Fig. 1, formed by funnel 14, inserted and fitting tightly into member 73; the top end of funnel 14 carries member 74, provided 20 with air inlet 15, and conically shaped extension 16 receiving tail-piece member 77, extending downwardly at a suitable depth into extension 76, thus forming annular space 78, and injector like contrivance to allow the air to rush in under 25 the action of the onrush of the water from flush valve 9, thus preventing the water from overflowing from the funnel. Tail piece 77 is provided with flange 78 and ports 16, and is threaded to receive flanged nut 79 to tighten tail-piece 30 77 in position, which at the upper end carries flush valve 9, and is provided with air inlets 80, to supply air to the inside top of tail piece 77, to allow the water to flow freely from outlet 81 of flush valve 9. Control valve 82 is connected to 35 the water supply, the other end is connected to flush valve 9 by nipple 83; handle 8 is to operate the flush valve; 20 is the cover of the tank, to which is fastened the flush valve by flange 78 and nut 79, provided with packing 87; nut 85 is 40 provided under the undersurface with three ribs 88, thus forming three spaces large enough to convey all the water collected from any source by the tank, into the bowl, through annular space 89 and port holes 90, by tail-piece 91, the lower 45 end of which is connected to the bowl; the air supplied into the tank, enters from ports 92 located in any suitable place on the tank. This form of the invention does not differ from the others, except that the flush valve is not housed 50 in the tank, but it houses the mechanism preventing back-siphoning, which receives the air supply from the inside of the tank, entering through openings suitably located on the walls of said tank. To allow the water to flow freely from 55 the outlet of the flush valve into the bowl, the air also is provided from the inside of the tank, same as in the other types above described, and finally, any leakage dropping into the tank is collected by the same, and conveyed into the 60 bowl, the same as in the other forms of the invention. This tank can be of the ordinary type at present in use, and therefore, can be fastened to the wall; old tanks can also be used by making on them the required perforations for the parts 65 that have to be attached thereto, or housed therein. The flush valves at present in use, none of which are 100% siphon-proof are made relatively safe by means of vacuum breakers and check valves, but when used in combination with this 70 apparatus, as shown in Fig. 9, all types of flushing valves are made 100% siphon-proof without the aid of any of the above mentioned, unreliable contrivances.

75 From the foregoing description, it will be seen that the purpose of my invention has been ac-

complished by the device as shown, economically and without complications, and by having reduced to practice said invention, the advantages described herein have proven to be real facts.

Obviously, other forms will readily suggest 5 themselves, it is therefore my intention to include all such forms and modifications of my invention that come within the range and scope of the invention, as expressed in the appended claims. 10

What I claim as my invention and desire to secure by Letters Patent, is:

1. In a water closet having a bowl, means for directing water into said bowl, and a tank surrounding said means and having a passage in 15 constant communication with the bowl whereby any fluid in the tank will drain into the bowl.

2. In a water closet having a bowl, a tank, a conduit connecting the bowl and tank, means for admitting air into the tank, means for admitting 20 air from the tank into said conduit above the water level in the bowl, and a flush valve discharging into the conduit, said valve having its discharge end in the tank above the maximum level that can be attained by the water in the 25 bowl.

3. The combination with a toilet bowl having a flushing valve therefor, of a housing for said flushing valve, said housing being provided with means for directing any water accumulating in 30 the housing into said toilet bowl, and separate means for discharging fluid from the flush valve into the bowl.

4. In a water closet comprising a bowl and a flushing valve therefor having means associated 35 therewith for directing fluid from the valve into the bowl, the combination with a housing for said flushing valve, said housing being provided with means for directing any water accumulating therein into the bowl. 40

5. In a water closet having a bowl, the combination of a flushing valve therefor, means for directing fluid from the valve into the bowl, and other means for collecting leakage from the 45 valve and directing it into the bowl.

6. In a water closet having a bowl, the combination of a flush valve discharging into said bowl, an auxiliary valve for controlling operation of the flush valve, means for operating the auxiliary valve to permit the flush valve to open, a 50 housing for said valves, said auxiliary valve having an outlet discharging into the housing, and means for directing fluid from the same into the bowl.

7. In a water closet having a bowl, a tank 55 above the bowl, a flushing valve housed in the tank, said tank having an opening therein communicating with the bowl, and being vented to atmosphere, means for directing fluid from the valve into the bowl, the discharge end of said 60 valve being sufficiently above the maximum level that can be attained by fluid accumulating in the tank to permit air to be drawn from the tank into said valve discharge upon occurrence of vacuum in the supply line. 65

8. In a water closet having a bowl, a tank, a fluid conduit passing through the tank and discharging into the bowl, means for admitting air to the tank and from the tank into the conduit above the bowl, and means for directing any fluid 70 accumulating in the tank into the bowl.

9. In a water closet having a bowl, a tank having an outlet communicating with the bowl, a flushing valve, means within the tank for directing fluid from the valve into the outlet from the 75

tank, said means being vented to atmosphere above the level of the bowl, and means for directing fluid accumulating in the tank into the bowl.

10. In a water closet having a bowl, a tank, a flushing valve for the bowl having a supply line communicating therewith, means within the tank for breaking a vacuum in the supply line, said tank having a passage in constant communication with the bowl to drain any accumulation of fluid therein into the bowl.

11. In a water closet having a bowl, a flushing valve therefor, a housing for the valve, an auxiliary valve controlling operation of the flushing valve and means for constantly supplying air to the lower face of the auxiliary valve from said housing.

12. In a water closet having a bowl, a supply line therefor, a strainer and pressure reducing valve in said supply line, a flushing valve receiving fluid from the reducing valve, an auxiliary valve communicating with the flushing valve and controlling operation of the same, a housing for said strainer, reducing valve, flushing valve and auxiliary valve, said housing communicating with the bowl, whereby any leakage accumulating in the tank will drain into the bowl, and means for operating the auxiliary valve.

13. In a water closet a bowl having a rim and provided with two passages communicating therewith, a tank above the bowl having openings communicating with said passages, means for directing scouring and refilling fluid to the bowl through one opening and passage, the other opening and passage conveying fluid accumulating in the tank into the bowl.

14. In a water closet including a bowl having a rim provided with two passages communicating therewith, a tank above the bowl having openings registering with said passages, a flushing valve in the tank discharging through one opening and passage to the bowl, a water hammer cushioning device in the other opening and passage and a fluid supply line for directing fluid to the flushing valve through the water hammer cushioning device.

15. In a water closet including a bowl having a rim provided with two passages communicating therewith, a tank above the bowl having openings registering with said passages, a flushing valve in the tank discharging through one opening and passage to the bowl, a water hammer cushioning device in the other opening and passage spaced from the walls thereof, and a fluid supply line for directing fluid to the flushing valve through the water hammer cushioning device, the space between the cushioning device and the walls of the opening and passage permitting fluid accumulating in the tank to drain into the bowl.

16. In combination with a water closet bowl, a housing, a water supply conduit in said housing and a valve on said conduit within said housing, said housing having drainage means in constantly open communication with said bowl.

17. In combination with a water closet bowl, an open housing, a water supply conduit extending into said housing, and a manually operated valve on the discharge end of said conduit within said housing, said valve having a discharge outlet within the housing, said housing being in open communication at all times with the bowl.

18. In combination with a water closet bowl, an open housing, and a water supply valve in said housing, said valve having an open discharge outlet within the housing, said housing being in

open communication at all times with the bowl, said discharge outlet of the valve having a foraminated discharge member.

19. In combination with a water closet bowl, a housing, water supply means within said housing for flushing the bowl, and flush water conducting means from the housing to the bowl in communication with the housing, said housing having an additional open passage communicating with said bowl for draining water from the housing into the bowl.

20. In combination with a water closet bowl, a receptacle, a valve controlled water supply means in said receptacle, a jet supply means for the bowl connected to said valve, water supply means for the rim of said bowl in open communication with said receptacle and means for providing open communication between the interior of said receptacle and the atmosphere; said receptacle having an additional unobstructed connection with the bowl to drain said receptacle into the bowl.

21. In combination with a water closet bowl, means for preventing back siphoning of the bowl comprising a receptacle having open communication with the atmosphere, a water supply pipe extending into the receptacle, a valve on said pipe, and a flush water connection from said receptacle to the bowl arranged to receive water from said valve, said water connection extending into said receptacle and having its ends spaced from the discharge end of the supply pipe and having open communication with the interior of said receptacle.

22. In combination with a water closet bowl, a receptacle, a valve controlled water supply means in said receptacle, a jet supply means for the bowl connected to said valve, water supply means for the rim of said bowl in open communication with said receptacle, and means for providing open communication between the interior of said receptacle and the atmosphere; said jet supply means forming clamping means for securing said receptacle to the bowl.

23. In combination with a water closet bowl, a receptacle, a valve controlled water supply means in said receptacle, a jet supply means for the bowl connected to said valve, a water passage for the rim of said bowl in open communication with said receptacle, and means for providing open communication between the interior of said receptacle and the atmosphere.

24. A device of the class described, comprising a flush pipe, a casing of larger diameter than the pipe and surrounding and attached to a portion of the same, said casing having an opening therein and that portion of the pipe surrounded by the casing having an opening therein for placing said portion in communication with the bottom of the casing.

25. In a flushing device for toilet bowls, a tank above the bowl, a water supply pipe extending into the tank having an open discharge end in the tank above the water level in the tank, a control valve in said water supply pipe, a water receiving pipe below the open end of the water supply pipe and a funnel on the upper end of the water receiving pipe spaced apart from the discharge end of the supply pipe.

26. In a flushing device for toilet bowls, a tank above the bowl, a water supply pipe extending into the tank having an open discharge end in the tank above the water level, a control valve in said water supply pipe, and a water receiving conduit below the water supply pipe having its

upper end spaced apart from the discharge end of the water supply pipe.

27. In a flushing device for toilet bowls, a tank above the bowl, a water supply pipe extending into the tank having an open discharge end in the tank above the water level in the bowl, and a water receiving conduit below the water supply pipe having its upper end in the tank and spaced apart from the discharge end of the water supply pipe.
28. A device of the class described, comprising a flush pipe, a casing of larger diameter than the pipe surrounding the same, said casing having an opening therein and that portion of the pipe surrounded by the casing having an opening therein for placing said portion in communication with the casing.
29. In a flushing device for toilet bowls, a bowl having a hollow rim provided with spaced perforations, a pipe for supplying flushing water to the rim and through the perforations into the bowl, the combined areas of the perforations being so proportioned with reference to the internal diameter of the supply pipe that spilling of water from said flushing device is prevented.
30. In a flushing device for toilet bowls, a bowl having a hollow rim provided with spaced perforations, a flush valve for admitting flushing water to the bowl, a container housing the flush valve and having communication with the bowl rim, and a pipe for supplying water to the flush valve, the combined areas of the perforations being so proportioned with reference to the internal diameter of the supply pipe that spilling of water from said flushing device is prevented.
31. In a flushing device for toilet bowls, a tank above the bowl, a water supply pipe extending into the tank having an open discharge end in the tank above the water level in the bowl, and a water receiving conduit below the water supply pipe having its upper end in the tank and spaced

apart from the discharge end of the water supply pipe, said water receiving conduit having an opening therein for placing said pipe in communication with the bottom of the tank.

32. In a flushing device for toilet bowls, a supply pipe, a flushing valve having a discharge end, means for directing fluid discharged from said end into the bowl, said discharge end constantly communicating with atmosphere and being spaced from the maximum level which can be attained by the water in the bowl a distance at least substantially equal to the internal area of the supply pipe, and a housing surrounding the valve and directing means and in constant communication with the atmosphere.

33. In a flushing device for toilet bowls, a container for the flushing device, a supply pipe, a pipe spaced from the supply pipe and receiving water therefrom and directing the same into the bowl, the space between the pipes being in communication with atmosphere, said communicating space and the walls of the container surrounding the communicating space being so proportioned as to prevent sufficient increase in velocity of air moving toward the supply pipe under the action of vacuum in the supply pipe line to create back siphoning, said toilet bowl having a rim provided with perforations, the combined areas of the perforations being so proportioned with reference to the internal diameter of the supply pipe line that the water will be prevented from spilling from said container.

34. In a flushing device for toilet bowls, a supply pipe, a flushing valve in said pipe behind the bowl, means for directing fluid discharged from the valve into said bowl, a housing having side walls surrounding the valve and directing means, and an operating handle for the valve projecting through one of said side walls in a direction transverse of the longitudinal axis of the bowl.
